[57] CLAIM

The ornamental design for an electrical connector for
appliances, as shown and described.

DESCRIPTION

FIG. 1 is a top plan view of an electrical connector for
appliances showing our new design, the bottom plan
view being plain and unornamented;
FIG. 2 is a left side elevational view thereof, the right
side elevational view thereof being a mirror image;
FIG. 3 is a left end elevational view thereof;
FIG. 4 is a right end elevational view thereof;
FIG. 5 is a perspective view thereof.

FIG. 1

FIG. 2

FIG. 3

FIG. 4

FIG. 5
